UNITED STATES PATENT OFFICE.

DONALD BARNS MORISON, OF HARTLEPOOL, ENGLAND.

METHOD OF AND APPARATUS FOR PREVENTING THE ABSORPTION OF AIR BY BOILER-FEED WATER OR OTHER LIQUID.

Application filed March 30, 1920. Serial No. 370,056.

To all whom it may concern:

Be it known that I, DONALD BARNS MORISON, a subject of the King of Great Britain, and resident of Hartlepool, England, have 5 invented certain new and useful Improvements in Methods of and Apparatus for Preventing the Absorption of Air by Boiler-Feed Water or Other Liquid, of which the following is a specification.

10 When water or other liquid is free of air or is in a condition of aeration below the normal, it readily absorbs air especially if the liquid is turbulent. For example, when condensate from a steam condenser is 15 brought into contact with air, the condensate readily absorbs air and the aeration of the condensate is prejudicially increased.

The object of my invention is to prevent this air absorption and the principle underlying the invention is to replace the air normally in contact with water by steam at a suitable pressure.

According to my invention the air absorption is prevented by placing the absorbing 25 surface in a chamber and admitting to the chamber steam or vapour for the purpose of excluding the air from the surface of the liquid. The steam may be admitted in such quantity and at such pressure as will cause 30 a continuous outflow from the chamber, it may be through a non-return valve whereby the chamber is maintained full of steam to the practical exclusion of admitted air.

In the accompanying drawings I have 35 illustrated diagrammatically means whereby my invention may be carried into practice. In these drawings Fig. 1 is a sectional view of a simple form of apparatus.

Figs. 2 and 3 illustrate further modifications.

Referring to these drawings and particularly to Fig. 1 the numeral 1 designates a tank which is closed and sealed by a cover-plate 2. Water flows through this tank by 45 way of the pipes 3 and 4 and air absorption is prevented by the admission of steam which circulates continuously through the tank by way of the pipes 5 and 6.

In Fig. 2 I have shown the application of 50 my invention to a recording device for measuring the flow of liquid. In this figure the recording device or stylus not shown is controlled by the float 18 in the usual way. The water enters the closed tank 19 by way

of the pipe 20, and flows through the V 55 notch 21, passing out through the pipe 22 in accordance with the usual practice. Air absorption is prevented or minimized by the admission of steam through the pipe 23 whence it flows in a continuous stream 60 through the closed tank 19 and passes out through the non-return valve 24.

In Fig. 3 a somewhat similar arrangement is shown. In this case the water enters the tank 25 by way of the pipe 26 and flows 65 through the opening 27 in the partition 28 to the air sealed chamber 29 whence it flows through the V notch 30 to the lower level, as indicated in the drawing, this level being maintained by the weir 31 at a height sufficient 70 to ensure the sealing of the chamber 29. Steam is admitted to this sealed chamber 29 through the pipe 32 and passes out by way of the pipe 33 which may be filled with a non-return valve indicated at 34. It 75 will be understood that the arrangements hereinbefore specifically described and illustrated are given by way of example only and do not exhaust the possible methods of carrying my invention into practice.

For instance, the invention can be applied advantageously to feed tanks maintained under any suitable pressure either above or below the atmosphere and particularly in tanks in which feed water is deaerated by being 80 heated and maintained in active circulation as by a steam jet.

It will be appreciated from the foregoing that the steam has two possible functions. In the first place it blankets the exposed surfaces and prevents any air getting into contact with it, and secondly it may act as a carrier to carry off any air which may, in some circumstances, be given off. The aerated steam which passes off may be led to 85 an auxiliary condenser or suitably elsewhere.

What I claim and desire to secure by Letters Patent is:—

1. The method of preventing degassed liquid from re-absorbing gases in a container 100 said method consisting in causing the liquid to enter and leave the closed container below the water level in said container whereby the surface of said liquid is maintained quiescent and causing a current of the vaporized liquid to flow continuously across the whole surface of the liquid within the container.
2. The method of preventing degassed 105

water from re-absorbing gases in a container
said method consisting in causing the water
to enter and leave the container beneath the
level within the container whereby the sur-
face of the water is maintained quiescent
and causing a current of steam to pass con-
tinuously across the whole surface of the
water in the container.

3. In means for preventing aeration of
water, a container through which the water
is caused to flow, a water inlet to said con-
tainer located beneath the water level in
said container, an outlet through which said
water passes, a steam inlet connection at one
extreme end of said container located above
the surface of the water, and a steam outlet

connection at the other extreme end of said
container.

4. In means for preventing aeration of
water a container through which the water 20
is caused to flow, a water inlet to said con-
tainer located beneath the water level in
said container, an outlet through which said
water passes, a steam inlet connection at one
extreme end of said container located above 25
the surface of the water, and a steam outlet
connection at the other extreme end of said
container and a check valve in the steam
outlet connection.

In testimony whereof, I affix my signa- 30
ture.

DONALD BARNES MORISON.
